UNITED STATES PATENT OFFICE

2,366,648

ROTARY TAKE-UP FOR SEWING MACHINES

Frank Parry, Bridgeport, Conn., assignor to The Singer Manufacturing Company, Elizabeth, N. J., a corporation of New Jersey

Application September 3, 1942, Serial No. 457,149

9 Claims. (Cl. 112—248)

This invention relates to rotary thread take-up mechanisms for sewing machines and, more particularly, to devices for preventing abnormal winding of thread about a rotary thread take-up member.

The present invention has for an object to provide means which will insure the severing of thread winding abnormally about the take-up member and which can be readily positioned by an unskilled operator to perform its thread-severing function. Another object of the invention is to provide means for throwing the severed end of the thread out of the path of rotation of the take-up member.

With these and other objects in view, as will hereinafter appear, the invention consists in the devices, combinations and arrangements of parts described in connection with the accompanying drawing, which illustrates a preferred embodiment of the invention and in which:

Fig. 1 is a front end elevation of the bracket-arm head of a sewing machine containing the improved thread-severing device. Fig. 2 represents an enlarged section of the rear take-up mechanism and taken substantially on the line 2—2 of Fig. 1, with the thread-severing element disposed in the slot of the take-up member. Fig. 3 represents an enlarged section taken on substantially the line 3—3 of Fig. 1, with the take-up member advanced into substantially the position shown in Fig. 2. Fig. 4 represents an enlarged view, partly in section, of the rear take-up mechanism as illustrated in Fig. 1, and shows the thread wound abnormally about the take-up member.

The present improvement has been embodied in a thread take-up mechanism corresponding in general to those disclosed in the U. S. patents of S. Zonis, No. 2,191,736, February 27, 1940, and No. 2,263,533, November 18, 1941.

The sewing machine in part illustrated in the drawing has a frame including a bracket-arm head 10. Journaled for vertical reciprocation in the bracket-arm head 10 is a needle-bar 11, carrying at its lower end a needle 12; said needle-bar being reciprocated by any usual or suitable actuating connections with a horizontally disposed main actuating shaft 13.

The main shaft 13 carries at one end thereof a main or front take-up disk 14 provided eccentrically of the axis of rotation of the shaft 13 with a pair of radially equidistant thread-engaging studs 15. The studs 15 carry a flat thread-confining ring 16 held spaced from the disk 14 axially of the main shaft 13. Being carried by

the main shaft 13, the disk 14 and the thread-engaging studs 15 perform one rotation for each complete reciprocation of the needle 12 and in a counterclockwise direction when viewed as in Fig. 1 of the drawing.

The thread-controlling mechanism also in-

cludes a supplemental rear take-up device. A

rotary shaft 17 is disposed parallel to the main-

shaft 13 and is actuated as described in said prior

Patent No. 2,191,736, or in any other suitable or

preferred manner, to perform two rotations for

each rotation of and in the same direction as the

main shaft 13. Carried by the supplemental shaft 17 for rotation therewith is a primary

thread-confining element in the form of a disk

18, which preferably is disposed in substantially

the same vertical plane as the front take-up disk

14.

Carried eccentrically by the supplemental take-

up disk 18 to extend from a side face of said disk

is a thread-engaging member 19 rotatable in an

orbital path about the longitudinal axis of the

shaft 17. The member 19 is somewhat elongated

in its orbital path, being in general of kidney

shape. In its side face opposite to the disk 18,

the member 19 is provided between the radially

outer and inner faces thereof with an arcuate

slot 20, which is preferably concentric with the

orbital path of the member 19. The slot 20 ex-

tends lengthwise throughout the member 19 so

as to be open at the opposite ends of said mem-

ber. Depthwise, the slot 20 extends transversely

of the side face of the disk 18 and also prefer-

ably extends across the effective thread-engag-

ing width of the member 19, as limited by the

disk 18. In effect, therefore, the slot 20 divides

the member 19 into two separate members ex-

tending from the disk 18 and spaced from each

other on a common radius. Concentric and co-

planar thread-confining flat rings 21 and 22 are

spaced axially from the disk 18; said rings being

spaced from each other to provide therebetween

a circular severing-element clearance slot 20'

constituting a continuation of the thread-en-

gaging member slot 20. The rings 21 and 22

are carried by the outer end of the member 19

so as to be disposed coaxial with the disk 18.

Attached to the bracket-arm head 10, by screws

as 23, is a face-plate 24 which is provided between

the front and rear take-up devices with a thread-

confining plate 25 suitably secured upon the face-

plate 24. The plate 25 has reversely curved op-

posite side edges disposed in proximity to the

orbital paths of the front take-up studs 15 and

the rear take-up member 19.

Suitably secured to the lower portion of the plate 25 and held separated therefrom by a spacer-plate 26 is a supplemental thread-confining plate 27 shaped similarly to the plate 25. The spaced upper portions of the plates 25 and 27 provide therebetween a thread-clearance slot 28.

The supplemental plate 27 is provided in its outer face opposite to the spacer-plate 26 with a recess 29; said recess forming a seat for the shank 30 of a thread-severing element 31. The severing-element shank 30 has an enlarged aperture 32 to receive a securing screw 33 threaded into the plate 27; said aperture permitting limited endwise adjustment of the shank 30 in a direction substantially radially of the orbital path of the thread-engaging member 19. The severing-element 31 is bent so that it extends substantially normal to its shank 30 and into the thread-engaging member slot 20 in a direction transverse to the orbital plane of the member 19. The severing-element 31 has a thread-cutting edge 34 at the side of said element first approached by the thread-engaging member 19 in the rotation of said member, and the member 19 is preferably provided lengthwise of its radially outer face with a thread-receiving groove 19'.

The two take-up devices are partly covered by a guard-plate 35 having an inwardly extending peripheral flange 36 directed toward and spaced from an outwardly extending peripheral flange 37 of the face-plate 24; said flanges 36 and 37 providing therebetween a thread clearance.

Supported upon the outer face of the guard-plate 35, adjacent the thread-severing element 31, are divergently extending arms 38 and 39 secured by a screw 40 for angular adjustment relatively to each other. The arm 38 carries a bent thread-supporting and -deflecting element or finger 41 which has its free end portion extending through the central opening of the thread-confining ring 22 transversely of and at an inclination to the orbital plane of the member 19 to terminate in a face-recess 42 provided in the take-up disk 18 centrally of said disk. The other arm 39 similarly carries a bent thread-supporting and -deflecting finger 43 which also extends through the inner thread-confining ring 22 transversely of and at an inclination to the orbital plane of the member 19 to terminate in the disk-recess 42. The free end portions of the fingers 41 and 43 are disposed closely adjacent to the orbital path of the member 19 and converge outwardly away from said path; said free end portions of the fingers 41 and 43 being respectively disposed fore and aft of the substantially constant point in the orbital path of the member 19 at which an abnormal winding of thread about said member is severed.

The needle-thread *t* extends from the conventional tension-device 44 about a thread-controlling guide 45 from which the thread passes upwardly and forwardly to overlie the thread-controlling member 19 of the rear take-up and the thread-engaging studs 15 of the front take-up in the lead of the thread to the needle 12.

As the free end portions of the thread-deflecting fingers 41 and 43 are disposed inside the orbital path of the thread-engaging member 19 in the region of the thread-severing element 31, the slack thread given up by the member 19 is normally supported by said fingers and prevented thereby from engaging said element 31.

It is self-evident that so long as the take-up element 19 remains entirely below the thread *t*, whether or not the thread is broken between the

take-up and the work, the thread cannot wind about the member 19, even in the absence of the fingers 41 and 43. However, it may happen in the event of thread-breakage that a bight of the loose thread is thrown in advance of the take-up member 19, whereby said member 19 gets on top of the thread. The thread thereupon starts abnormally to wind about the member 19, as illustrated in Fig. 4 of the drawing.

10 In winding circumferentially about the member 19, the coils of thread necessarily pass across the leading end of the slot 20. As the thread-severing element 31 traverses the slot 20 in each rotation of the take-up member, the thread extending across the leading end of the slot 20 is severed by the cutting edge 34 of the severing element 31.

15 It is unnecessary for the severing element 31 to coact with the member 19 to shear the thread and it will, therefore, be understood that the set position of the element 31 is not critical. In fact, it is not vital to have the edge of the severing element 31 sharpened, because the thread when wound about the member 19 will inevitably be broken by the element 31.

20 The thread-supporting and -deflecting finger 41 is disposed slightly in advance of the thread-severing element 31 in the direction of approach of the member 19 to the severing element 31. In the normal operation of the machine, the finger 41 opposes movement of slack thread into a position wherein it might be carried by the member 19 into engagement with the severing-element 31. When the thread is abnormally wound about said member 19, as illustrated in Fig. 4, the thread is partly wrapped about the finger 41 just prior to severing of the thread by the element 31. Owing to the inclination of the finger 41 with respect to the orbital plane of the member 19 and the direction of rotation of said member as indicated by an arrow in Fig. 4, the finger 41 tends to force the thread outwardly away from said plane. As the thread is severed during this outward movement thereof along the finger 41, the severed length of thread is thrown outwardly away from the take-up. The finger 43 is not only complementary to the finger 41 in normally supporting the slack thread free of the severing-element 31, but it also assists in throwing the severed end of the thread away from the take-up, by reason of the outward convergence of the fingers 41 and 43.

25 Having thus set forth the nature of the invention, what I claim herein is:

30 1. In a sewing machine, a thread take-up device comprising, a disk rotatable about a fixed axis, a thread-engaging member extending from a side face of said disk eccentrically to said axis, said member being provided with a severing-element clearance slot extending depthwise transversely of said face of said disk, thread-confining means carried by said member in laterally spaced relation to said disk, and a thread-severing element disposed to traverse said slot in the rotation of said member.

35 2. In a sewing machine, a thread take-up device comprising, a disk rotatable about a fixed axis, a thread-engaging member extending from a side face of said disk eccentrically to said axis, said member being provided with a severing-element clearance slot extending depthwise transversely of said face of said disk, radially spaced and concentric thread-confining elements carried by said member in laterally spaced relation to

said disk, said elements providing between them a clearance slot in circular alignment with the slot of said member, and a stationary thread-severing element disposed to traverse said slot in the rotation of said member.

3. In a sewing machine, a thread take-up device comprising, a disk rotatable about an axis, a thread-engaging member carried by and extending laterally from said disk eccentrically to the axis of rotation of said disk, said member being provided with a severing-element clearance slot lengthwise extending in the orbital path of said member and depthwise extending transversely of a side face of said disk, a pair of substantially flat and coplanar rings of different diameters carried by said member in spaced relation to said disk, said rings being concentric with said disk and being spaced from each other to provide therebetween a clearance slot in circular alignment with the slot of said member, a stationary thread-severing element disposed to traverse said slot in the rotation of said member, and supporting means for said element.

4. A thread take-up mechanism for sewing machines, comprising, a thread-engaging member having an orbital path of rotation and about which member the thread may abnormally wind, thread-severing means associated with said member for severing the thread when abnormally wound about said member, and a stationary thread-supporting and -deflecting element extending across the orbital plane and within the path of rotation of said member, said element being inclined to said plane in a direction to deflect the thread away from said plane.

5. A thread take-up mechanism for sewing machines, comprising, a thread-engaging take-up member having an orbital path of rotation and about which member the thread may abnormally wind, thread-severing means associated with said member for severing the thread when abnormally wound about said member, and thread-supporting and -deflecting fingers disposed adjacent said severing means and extending across the orbital plane and within the path of rotation of said member, said fingers being convergent in a direction away from said plane.

6. In a sewing machine, the combination with a thread-engaging take-up member having an orbital path of rotation and about which member the thread may abnormally wind, and means effective at a substantially constant point in said orbital path for severing thread abnormally wound about said member, of stationary thread-supporting and -deflecting fingers extending across the orbital plane and within the orbital path of rotation of said member, said fingers being disposed fore and aft of said point and being convergent in a direction away from said plane.

7. In a sewing machine, the combination with a thread-engaging take-up member having an orbital path of rotation and about which member the thread may abnormally wind, and means effective at a substantially constant point in said orbital path for severing thread abnormally wound about said member, of stationary thread-supporting and -deflecting fingers extending across the orbital plane and within the orbital path of rotation of said member, said fingers being disposed fore and aft of said point and being convergent in a direction away from said plane, and supporting means providing for adjustment of said fingers relative to each other.

8. A thread take-up device for sewing machines, comprising, a disk, a member carried by and extending laterally from said disk eccentrically of the center of said disk, said member being provided in its side face opposite to said disk with a slot lengthwise extending circumferentially of said disk, said slot extending depthwise transversely of a side face of said disk, and a pair of substantially flat and coplanar rings carried by said member at opposite sides of said slot.

9. A thread take-up device for sewing machines, comprising, a disk, a pair of members extending laterally from said disk eccentrically of the center of said disk, said members being spaced from each other radially of said disk to provide a clearance slot between the members, and concentric rings carried by said members in spaced relation to each other and to said disk.

FRANK PARRY.
